UNITED STATES PATENT OFFICE.

JAMES DUNN, OF BRIDGEPORT, CONNECTICUT, ASSIGNOR TO THE WARNER BROTHERS COMPANY, OF BRIDGEPORT, CONNECTICUT, A CORPORATION OF CONNECTICUT.

PAPER-BOX BLANK.

1,107,048.

Specification of Letters Patent. Patented Aug. 11, 1914.

Application filed December 20, 1912. Serial No. 737,811.

To all whom it may concern:

Be it known that I, JAMES DUNN, a citizen of the United States of America, and a resident of Bridgeport, Fairfield county, Connecticut, have invented a new and useful Improvement in Paper-Box Blanks, of which the following is a specification.

My invention relates to a paper box blank of the kind especially adapted to the manufacture of folding or knockdown paper boxes of the type used as mailing boxes and the object of the invention is to provide for the manufacture of such boxes with the least waste of material and at the least possible cost of making.

A further object of the invention is to provide a structure which may be easily set up by inexperienced labor and which will be strong and secure in use.

In the following I have described, in connection with the accompanying drawings, a paper box blank embodying the principles of my invention, the features thereof being more particularly pointed out hereinafter in the claims.

In the drawings Figure 1 is a plan view of a paper box blank illustrating one way of practising my invention; Fig. 2 is a perspective view of the outer envelop or container set up from a portion of the blank shown in Fig. 1 and Fig. 3 is a perspective view of the tray set up from another portion of said blank and adapted to be slid within or inclosed by the envelop shown in Fig. 2.

Similar letters of reference indicate similar parts throughout the several views.

In the drawings *a* indicates a substantially rectangular piece of paper box board 40 constituting the primary blank. A portion to the lefthand, the upper, righthand and a portion of the lower edges form respectively the outer edges of that portion of the blank adapted to form the envelop shown 45 set up in Fig. 2. Another portion of the lower edge of the board *a* forms one of the outer edges of that portion of the blank adapted to form the tray shown set up in Fig. 3.

50 The dotted lines *b*, *c*, *d*, *e*, *f*, *g*, *h* and *i* indicate scorings on that portion of the blank adapted to form the envelop and dotted lines *j*, *k*, *k'*, *k''*, *l*, *m*, *n*, *o*, *p* and *q* indicate scorings on that portion of the 55 blank adapted to form the tray.

Full lines *r*, *s*, *t*, *u*, *u'*, *v*, *v'*, *w*, *w'*, *x*, *x'* and *y*, *y'* indicate cuts in the blank to sever the two portions of the blank from each other and to form said separated parts into secondary blanks adapted to be set up into the envelop and tray. 60

z indicates a cut to form a thumb hole in the envelop.

It will be observed that all of the scorings and cuts may be made by a single impression or stroke of a suitable die and that the only waste portions of the primary blank, in the form shown, are for the thumb hole *z*, the corners adjacent cuts *y* and *y'* and the narrow rectangular strip to the left of cuts *r* and below cut *r*. 70

In setting up the secondary blanks to form the envelop and tray respectively, the portion adapted to form the envelop is folded along the scorings *b*, *c*, *d* and *e* to form a 75 tube and the narrow strip adjacent scoring *b* is pasted or otherwise secured adjacent the outer righthand upper edge of the secondary blank. The flap portion of the envelop is then folded along the scorings *f*, *g*, *h* and *i* to pass across the ends and one side of the envelop as shown in Fig. 2, the tongue *A* being adapted to be tucked into the envelop adjacent thumb hole *z*. The tray is formed by folding the other secondary blank along 85 the scorings *k'*, *k''*, *n*, *p*, *o*, *q*, *k*, *l*, *j* and *m* so that flaps *B* and *B'* and *C* and *C'* lie adjacent the ends of the tray and flaps *D* and *D'* are bent over the upper edges of the end of the tray and down into the interior 90 thereof where they may be secured in any desired manner. I have shown flaps *D*, *D'* as wedge-shaped so that they may be crowded into the tray and held therein by friction.

It is obvious that the exact arrangement 95 shown and described may be varied without departing from the spirit of my invention and I do not restrict myself to such details further than the scope of the appended claims demand.

What I claim and desire to secure by Letters Patent is:

1. A blank for a paper box formed of a tray and a separable envelop inclosing said tray, comprising a substantially L-shaped portion including a main body portion for the envelop disposed at the angle of the L-shaped portion, a side body portion for the envelop, the opposite main body portion for the envelop and the opposite side body por- 105 110

tion for the envelop being arranged along the foot of the L, the stem of said substantially L-shaped portion being formed by flap portions for respectively covering one end of the envelop, one main body portion of the envelop and the opposite end of the envelop, substantially the entire remaining rectangular portion of the blank being scored and cut to form after separation from 10 said L-shaped portion the sides and bottom of said tray.

2. A blank for a paper box formed of a tray and a separable envelop inclosing said tray, comprising a substantially L-shaped portion including a main body portion for the envelop disposed at the angle of the L-shaped portions, a side body portion for the envelop, the opposite main body portion for the envelop and the opposite side body portion for the envelop being arranged integrally *in seriatim* along the foot of the L, the stem of said substantially L-shaped portion being formed by flap portions for respec-

tively covering one end of the envelop, one main body portion of the envelop and the 25 opposite end of the envelop, the remaining substantially rectangular integral portion of the blank being arranged to be cut from said envelop portion along the two inner edges of the L-shaped portions, said substantially rectangular portion including the bottom portion for the tray, two side portions for the tray, two end portions for the tray, and reinforcing portions integral with said two side portions of the tray respectively, 30 and flaps respectively secured to said end portions of the tray adapted when folded to inclose certain of said end reinforcing portions of the tray.

In testimony whereof I have signed this 40 specification in the presence of two subscribing witnesses.

JAMES DUNN.
